UNITED STATES PATENT OFFICE.

JOHN DADIE, OF CHICAGO, ILLINOIS.

METHOD OF MAKING SHORTENING.

No. 833,445.

Specification of Letters Patent.

Patented Oct. 16, 1906.

Application filed November 26, 1905. Serial No. 289,103.

To all whom it may concern:

Be it known that I, JOHN DADIE, a citizen of the United States, residing at Chicago, in the county of Cook and State of Illinois, have 5 invented certain new and useful Improvements in Methods of Making Shortening, of which the following is a full, clear, and exact description.

My invention relates to the aeration of 10 butter and oleaginous substances for various purposes, and particularly for the production of a satisfactory material to be used in the manufacture of bread, pastry, and the like.

In cooking bread and pastry oleaginous 15 material, such as butter, is required as "shortening," and it is also essential that when the shortening material is added it be in a divided or cellular state rather than in a compact mass. So far as I am aware it has 20 been customary for bakers to "beat up" the oleaginous material with sugar or some other ingredient of the article to be baked, thereby insuring its introduction in the requisite finely-divided state.

25 The principal object of my present invention is to produce shortening as an article of manufacture in a state ready for its introduction into the article to be baked.

A further object of the invention is to de- 30 vice a simple and convenient process for furnishing the above product.

With these and other objects in view my invention consists in the order, sequence, and character of steps and operations hereinafter 35 more fully described, and particularly pointed out in the appended claims.

Figure 1 is a sectional view illustrating a step of the process embodying my invention. Fig. 2 is a similar view illustrating the prod- 40 uct. Fig. 3 is a plan view, partly in section, of the apparatus, showing the construction of the churning-arms. Fig. 4 is a vertical section of the same.

The invention further consists in the com- 45 pleted product as particularly pointed out in the appended claims.

In carrying out my invention I make use of butter, butterine, lard, or any composition or mixture of oils or ingredients, and I pro- 50 vide means for thoroughly churning or beating such materials, so as to introduce and distribute a quantity of air in a finely-divided state therein.

A practical composition which I use to 55 apply the principles of my invention com- prises substantially thirty parts oleo-oil,

sixty parts neutral oil, and ten parts brine, which are mixed intimately together, so as to form a butterine product suitable for the purposes of making bread and pastry. By 60 the terms "oleo-oil" and "neutral" oil I refer to the compounds made from fresh beef fat and from lard by processes substantially as follows: Oleo-oil is an oil taken from fresh beef called "fat" and separated from 65 the stearin at a low temperature. This is done by applying hot air to the fat inclosed in bags in a press, thus separating the oil from the stearin after being reduced to a pulp by grinding or passing through a hasher 70 and melted at a temperature not higher than 122° Fahrenheit. Neutral oil is a product of lard made from the leaf-lard of the pig hashed, melted, and clarified at a low temperature and cooled in a manner that makes 75 it free from any taste or smell without any taint of hog or lard. It is a neutral lard of leaf-lard, colorless, and has no acid reaction. While these particular processes are used in practice for making oleo-oil and neutral oil, 80 I do not, of course, desire to be limited or restricted thereto, since my invention is equally applicable to oleo-oil and neutral oil made by any other processes than the ones above mentioned.

Having obtained this composition of oleo-oil, neutral oil, and brine in a suitably warmed and melted state, I place it within an ice-jacketed or otherwise cooled receptacle 1, through which churning or beating arms 2 90 may be propelled. The churning-arms 2 so provided have ducts or passages 3 there- through for the admission of air, so that when the arms rotate through the composition they will create cavities 4 therein into 95 which the air will be sucked through said ducts.

The composition above mentioned or any other composition of butterine, lard, butter, or oleaginous matter of any sort being 100 placed within said receptacle in a melted or otherwise softened state I apply power to move the apertured arms 2 therethrough, so that after a certain length of time the composition is thoroughly aerated and filled with 105 many cells or bubbles. The composition cools somewhat during the aerating process, so that the air supplied is retained in the mass and does not escape. The cooling, however, is not permitted to continue till 110 the mass is entirely solid, as this is unnecessary and would render the product difficult

to remove from the aerating apparatus. After aeration has thus taken place it is merely necessary to further and completely cool the composition, which causes a portion 5 of the air to become squeezed out and escape; but the mass retains nevertheless its flocculent and finely-divided character, entirely different from the solidity which is always characteristic of the above-named compositions in their natural state. In this condition it may be packaged for shipment or use in any convenient packing-receptacle. Its consistency is an integral homogeneous mass something like ordinary butter, except much 10 lighter and apparently drier, showing no water-bubbles when cut with a knife or broken open. Its properties are, however, wholly different, it being readily broken up when desired into crumbs or segregated particles, each having the flocculent or cellular structure above described.

In making bread or pastry it is merely necessary to supply a required quantity of

the flocculent product above obtained, which will make an efficient shortening without the 25 necessity of any further preparation or manipulation for subdividing it.

What I claim is—

1. As an article of manufacture, shortening comprising oleo-oil, neutral oil and brine 30 with many cells or air-bubbles throughout its substance in a condensed or compact condition.

2. The method of making shortening which consists in placing a mixture of oleo- 35 oil, neutral oil and brine in a suitably warmed and melted state in an ice-jacket or otherwise cooled receptacle, injecting air into the composition, and finally permitting it to cool and harden.

In witness whereof I subscribe my signature in the presence of two witnesses.

JOHN DADIE.
